Atty.

UNITED STATES PATENT OFFICE.

JOSEPH D. COUGHLIN, OF DORCHESTER, MASSACHUSETTS, ASSIGNOR TO FEDERAL MANUFACTURING COMPANY, OF BOSTON, MASSACHUSETTS, A CORPORATION OF MASSACHUSETTS.

TOGGLE.

1,222,850.

Specification of Letters Patent. Patented Apr. 17, 1917.

Application filed October 11, 1915, Serial No. 55,845. Renewed January 31, 1917. Serial No. 146,024.

To all whom it may concern:

Be it known that I, JOSEPH D. COUGHLIN, a citizen of the United States of America, and a resident of Dorchester, in the county 5 of Suffolk and State of Massachusetts, have invented certain new and useful Improvements in Toggles, of which the following is a specification.

This invention relates to toggles and has 10 for its object the production of a device of this character which will be simple in construction and very effective in its operation.

The invention consists in a metal plate 15 having struck therefrom midway of its length a locking tongue adapted to be jammed upon the end of a flexible member positioned in a transverse groove in the face of said plate opposite said tongue.

20 The invention further consists in certain novel features of construction and arrangement of parts which will be fully understood by reference to the description of the drawings and to the claim hereinafter 25 given.

Of the drawings:

Figure 1 represents a front elevation of a toggle embodying the principles of the present invention.

30 Fig. 2 represents a plan of the same.

Fig. 3 represents an end view of the same.

Fig. 4 represents a transverse section of the same on line 4—4 on Fig. 1.

Fig. 5 represents a rear elevation of the 35 plate showing the tongue struck therefrom, and

Fig. 6 represents a longitudinal section of the same on line 6—6 on Fig. 5.

Similar characters designate like parts 40 throughout the several figures of the drawings.

In the drawings, 10 is a thin metal plate having struck therefrom midway of its length a tongue 11. The portions of said 45 plate 10 on opposite sides of said tongue 11 are provided with the alined depressions 12 extending transversely of said plate.

One end of a flexible member 13 is positioned in said depressions 12 and then the tongue 11 is forced downwardly thereon 50 causing a bend in the flexible member as indicated at 14, thereby locking the member 13 to the plate 10. When the flexible member 13 has been secured to the plate 10 in the manner described, its center will be in 55 the same plane with the center of the thickness of said plate so that any strain upon the flexible member will pull the edge 15 of the plate 10 against the material in connection with which the toggle is to be used, 60 while retaining the side faces of the plate parallel with the center line of said flexible member.

The depressions 12 are formed in the plate 10 at the same time that the tongue 11 65 is struck therefrom.

The entire device is constructed in a simple manner from a minimum number of parts, and is readily assembled.

The material forming the depressions 12 70 and the tongue 11 may be compressed into the flexible member 13 to any desired degree.

It is believed that the operation and many advantages of a toggle constructed in this 75 manner will be obvious without further description.

Having thus described my invention, I claim:

A toggle adapted to grip a rope, consisting of a rigid plate having a depression midway of its length and extending transversely thereof, a tongue struck up from the center of the plate and opposite from the depression, whereby when a rope is placed 85 in the depression and the tongue forced down, the toggle will be held firmly upon the rope.

Signed by me at 4 Post Office Sq., Boston, Mass., this 2nd day of October, 1915. 90
JOSEPH D. COUGHLIN.

Witnesses:

WALTER E. LOMBARD,
NATHAN C. LOMBARD.
